LEVELER

Robinson H. Harsh, Washington, D. C.

Application July 24, 1936, Serial No. 92,467

6 Claims. (Cl. 16—19)

This invention relates to devices for leveling furniture and the like, on uneven floors and has for one of its objects the production of a simple and efficient equalizer which may be easily inserted in the lower end of a leg or other support of a piece of furniture and efficiently adjusted to fixedly hold the furniture in a level and stable position.

A further object of this invention is the production of a simple and efficient adjusting means for locking the supporting plunger of the equalizer in an adjusted position whereby the supporting plunger will be held against accidental movement after once being adjusted and at the same time may be easily further adjusted by the operator.

Another object of this invention is the production of an efficient bearing contact for the upper end of the supporting plunger and adjusting means, whereby the adjustment may be made with a minimum amount of effort in proportion to the weight supported by the plunger.

Other objects and advantages of the present invention will appear throughout the following specification and claims.

In the drawing:

Figure 1 is a side elevation of the lower end of a leg of a piece of furniture, a portion of the leg being shown in section;

Figure 2 is a vertical sectional view taken on line 2—2 of Figure 1;

Figure 3 is a transverse sectional view taken on line 3—3 of Figure 2;

Figure 4 is a transverse sectional view taken on line 4—4 of Figure 2;

Figure 5 is a transverse sectional view taken on line 5—5 of Figure 2;

Figure 6 is a vertical sectional view of the equalizer showing the supporting plunger in its fully retracted position;

Figure 7 is an enlarged vertical sectional view of the upper end of the supporting plunger and a portion of the equalizer casing, and showing the friction expansion ring for frictionally holding the plunger from dropping out of the casing;

Figure 8 is a vertical sectional view of a modified form of the equalizer;

Figure 9 is a vertical sectional view of a further modified form of the invention.

By referring to the drawing, it will be seen that A designates the leg of a table, chair, or other piece of furniture, or in fact any other article or means adapted to be supported. The leg A is provided with a socket 10 extending upwardly from its lower end, in which socket 10 is

fitted a casing 11 of the device for leveling furniture on uneven floors which might be preferably referred to as a leveler. This casing 11 is provided with a vertically extending bore 12 extending from the lower end toward the upper end and the casing 11 is also provided with a transversely extending internally threaded bore 13 extending at substantially right angles to the bore 12 and communicating with the top end of the bore 12, as shown in Figure 2. The leg A is also provided with a socket or bore 14 which communicates with one end of the internally threaded bore 13 for the purpose hereinafter described. The casing 11 is also provided with an annular flange or abutment means 15 at its lower end 15 for abutting against the lower end of the leg A and limiting the inward movement of the casing 11 within the socket or bore 10 of the leg A. The bore 12 is preferably circular in cross-section and is adapted to receive a plunger 16 which is also preferably circular in cross-section and fits within the bore 12. The plunger 16 is provided at its lower end with a gliding shoe 17 in the nature of a circular disc which constitutes a foot or shoe to rest upon the floor or other support and also limits the inward movement of the plunger 16 within the bore. The plunger 16 is also provided with an annular channel 18 within which fits a spring expansion ring 19 which is adapted to firmly grip against the walls of the bore 12 and frictionally hold the plunger 16 against accidental displacement from the bore 12—note particularly Figure 7. It should be noted that the bore 12 is located off-center of the longitudinal axis of the casing 11 in order to provide a sufficient purchase or bearing for the threads of the set screw 23.

A ball-bearing 20 is carried in the upper end of the bore 12 at the point of junction with the internally threaded bore 13 and a spring expansion ring 21 similar to the expansion ring 19 contacts with the under face of the ball-bearing 20 and the walls of the bore 12 to prevent the ball 20 from dropping out should the plunger 16 be removed. This ball-bearing 20 is free to rotate and is adapted to contact with the inclined face of the inner cone-shaped end 22 of the externally threaded set screw 23 which set screw 23 is threaded into internally threaded socket 13, as shown in Figure 2. The set screw 23 is slotted, as at 24, to permit a screw-driver to engage the set screw whereby the set screw may be rotated or adjusted within the internally threaded socket 13, the screw-driver being adapted to be inserted through the socket 14 as will be

obvious by considering Figure 2, and in the manner as shown in dotted lines in Figure 3.

The operation of the device is as follows:—

- As many leveling devices or levelers may be employed as desired, upon the various legs or other supporting portions of an article to be supported, and the socket 14 is preferably formed in the inner face of the leg where the same will be out of line of normal vision. The piece of furniture may be properly leveled by adjusting the set screw 23 upon the desired leg or portion of the piece of furniture and it should be understood that by threading the set screw 23 inwardly and forcing the cone-shaped end 22 against the ball-bearing 20, the plunger 16 may be forced downwardly thereby raising the leg A until the article or piece of furniture has been properly leveled. If it is desired to lower the leg A the set screw 23 may be retracted away from the ball-bearing 20 and the weight of the furniture or article will cause the plunger 16 to retract within the bore 12 until the ball-bearing 20 contacts again with the inclined face of the cone-shaped end 22 of the set screw or threaded plug 23.
- From the foregoing description it will be seen that a very simple and efficient means has been provided for minutely adjusting the leg of a table or other piece of furniture whereby the same may be leveled even when standing upon an uneven floor or other uneven surface. Furthermore, the adjustment of the set screw 23 will permit of the raising and lowering of the plunger 16 with a minimum amount of effort through the medium of a screw-driver and after the plunger has once been set, it will be practically impossible for the plunger 16 to get out of adjustment due to the fact that the set screw 23 will be contacted by the ball-bearing 20 which is interposed between the inclined face of the set screw 23 and the inner end of the plunger 16, there being no tendency, consequently, to rotate the set screw 23 merely by pressure of the ball-bearing 20 upon the cone-shaped end of the set screw 23.

In Figure 8, there is shown a modified form of the invention wherein I employ a casing 25 having a vertical bore 26 in which is slidably mounted a plunger 27 similar to the plunger 16, and a friction plug 28 is tightly fitted within the inner end of the bore 26 to constitute a means for holding the ball-bearing 29 (similar to the ball-bearing 20) against accidental displacement. I have also shown a set screw 30 slightly smaller than the set screw 23 and in this instance it is preferable to support the ball 29 in a position where the apex 31 of the inner cone-shaped end 32 of the set screw 30 extends slightly above the central axis of the ball-bearing 29 thereby causing the inclined face of the inner cone-shaped end of the set screw 30 to more effectively operate against the ball 29. The set screw 30 is threaded into the internally threaded socket 33 which extends at substantially right angles to the bore 26 and communicates with the inner end thereof. Where the larger set screw or plug is used, as is shown in Figures 2 and 6, the apex of the cone-shaped end 22 normally extends on a plane approximately at the upper end of the ball 20, as shown. The plug 28 is provided with a spring expansion ring 28a and the plunger 27 is provided with a spring expansion ring 27a for holding the parts in frictional set engagement with the walls of the bore 26.

As shown in Figure 9, which illustrates a further modified form of the invention, the plunger 35 is constructed similarly to the plunger 16 and

is provided with a spring expansion ring 36 for holding the plunger 35 within the bore 37 of the casing 38. This plunger 35 is provided with a rounded upper end 39 which is adapted to be engaged by the cone-shaped inner end 40 of the set screw 41 which is threaded into the internally threaded socket 42. The socket 42 extends at right angles to the bore 37 and communicates with the inner end of the bore. It will be seen that as the set screw 41 is forced inwardly within the threaded socket 42 a cone-shaped end 40 of the set screw 41 will engage the rounded upper end of the plunger 35 and cause the plunger 35 to be adjusted outwardly.

Having described the invention, what I claim as new is:—

1. A device of the class described comprising a casing having an off-center longitudinal bore, a plunger slidable in said bore, a ball contacting the inner end of said plunger, a friction plug 20 frictionally engaging said ball and the walls of said bore for preventing the accidental displacement of said ball, said casing having a transverse threaded bore near the inner end of said plunger, a set screw threaded in said transverse bore, and said set screw having a cone-shaped inner end having its inclined face contacting said ball whereby said plunger may be adjusted longitudinally of said casing as said set screw is manually adjusted inwardly against said ball, the set 30 screw by contacting the ball fixedly holding said plunger against accidentally retracting within the casing after once having been adjusted.

2. A device of the class described comprising a casing having a longitudinal bore, a plunger 35 slidably mounted within the bore and having a rounded inner end, said casing having a transversely extending internally threaded socket communicating with the inner end of said bore, a set screw threaded in said socket and having a 40 cone-shaped inner end for contacting with the rounded inner end of said plunger whereby said plunger will be adjusted longitudinally within said casing as said set screw is moved inwardly into binding contact with said plunger.

3. As an article of manufacture, a leveler for supporting legs of furniture and the like in a set adjusted position comprising a casing formed with a longitudinal bore and a transverse bore intersecting the longitudinal bore near the inner 50 end of the longitudinal bore, a weight supporting plunger slidable in the longitudinal bore and adapted to project beyond the outer end of the casing for engagement with a floor and the like, an adjusting screw threaded into the transverse 55 bore and having means contacting the inner end of the plunger to facilitate the adjustment of the plunger longitudinally of the casing, the adjusting screw extending at an angle to the plunger whereby the thrust of the plunger caused by the 60 weight of the article supported thereby will be exerted substantially transversely of the longitudinal axis of the adjusting screw thereby reducing the tendency to loosen the adjusting screw to a minimum.

4. As an article of manufacture, a leveler for supporting legs of furniture and the like in a set adjusted position comprising a casing formed with a longitudinal bore and a transverse bore intersecting the longitudinal bore near the inner 70 end of the longitudinal bore, a weight supporting plunger slidable in the longitudinal bore and adapted to project beyond the outer end of the casing for engagement with a floor and the like, an adjusting screw threaded into the transverse 75

bore, the inner end of the adjusting screw being cone-shaped, the inner end of said plunger carrying a rounded portion contacting the cone-shaped end of the adjusting screw to facilitate the adjustment of the plunger longitudinally of the casing, the adjusting screw extending at an angle to the plunger whereby the thrust of the plunger caused by the weight of the article supported thereby will be exerted substantially transversely 5 of the longitudinal axis of the adjusting screw thereby reducing the tendency to loosen the adjusting screw to a minimum.

5. As an article of manufacture, a leveler for supporting legs of furniture and the like in a set 15 adjusted position comprising a casing formed with a longitudinal bore and a transverse bore intersecting the longitudinal bore near the inner end of the longitudinal bore, a weight supporting plunger slidable in the longitudinal bore and adapted to project beyond the outer end of the 20 casing for engagement with a floor and the like, an adjusting screw threaded into the transverse bore, the inner end of the adjusting screw being cone-shaped, a ball supported by the inner end 25 of said plunger having rolling contact with the cone-shaped end of said adjusting screw to facilitate the adjustment of the plunger longitudinally of the casing, the adjusting screw extending at an angle to the plunger whereby the thrust of

the plunger caused by the weight of the article supported thereby will be exerted substantially transversely of the longitudinal axis of the adjusting screw thereby reducing the tendency to loose the adjusting screw to a minimum.

5

6. As an article of manufacture, a leveler for supporting legs of furniture and the like in a set adjusted position comprising a casing formed with a longitudinal bore and a transverse bore intersecting the longitudinal bore near the inner 10 end of the longitudinal bore, a weight supporting plunger slidable in the longitudinal bore and adapted to project beyond the outer end of the casing for engagement with a floor and the like, an adjusting screw threaded into the transverse 15 bore and having means contacting the inner end of the plunger to facilitate the adjustment of the plunger longitudinally of the casing, the adjusting screw extending at an angle to the plunger whereby the thrust of the plunger caused by the 20 weight of the article supported thereby will be exerted substantially transversely of the longitudinal axis of the adjusting screw thereby reducing the tendency to loosen the adjusting screw to a minimum, and the longitudinal bore being located off center of the longitudinal axis of the 25 center of the casing to provide ample purchase for the threads of the set screw.
